UNITED STATES PATENT OFFICE.

BRUNO PAUL BOHACEK, OF FRANKFORT-ON-THE-MAIN, GERMANY, ASSIGNOR TO THE CORPORATION OF MASCHINENFABRIK MOENNS A.-G., OF FRANKFORT-ON-THE-MAIN, GERMANY.

SKIN REST.

Application filed August 24, 1921. Serial No. 495,091.

(GRANTED UNDER THE PROVISIONS OF THE ACT OF MARCH 3, 1921, 41 STAT. L., 1313.)

To all whom it may concern:

Be it known that I, BRUNO PAUL BOHACEK, a citizen of the Kingdom of Hungary, residing at Frankfort-on-the-Main, 5 Germany, State of Prussia, have invented certain new and useful Improvements in Skin Rests (for which I have filed an application in Germany, Jan. 30th, 1914, Patent No. 296,531), of which the following is a 10 full, clear, and exact description.

The invention consists in a skin pressing and supporting device for machines for fleshing, shaving, scudding and similar treatment of hides and skins.

15 The object of the invention is to provide a work support in which the pressure may be regulated differently at different points of the whole length of the working surface of the support, and which provides 20 considerable pliancy, resiliency and local adaptability to the hide or leather.

25 In the accompanying drawings Fig. 1 is a sectional view of the device, Fig. 2 a view from above. Figures 3 and 4 are sectional views showing the different regulation of the pressure at different points.

30 The work support consists first of a rubber-ledge *c*, movable between guiding-plates *a*, off and towards the working roller *b*. An inflatable rubber tube *d* is provided at the 35 rear side of the rubber-ledge *c* in contact with it, and is controlled by counter-bearings *e e*, arranged in series over the length of the machine, to regulate the pressure at will at different points.

40 The counter-bearing *e e* is connected with a press screw *h* by a bolt *n*. A nut *k* is rotatably mounted in the encasing *i* and may be turned by a hand wheel *m*. The bolt *n* is guided in a slot *o* of the encasing.

45 The counter-bearing is composed of two pliable metal strips *e e* extending all over the length of the machine.

50 The rubber tube *d* is strengthened by inlaid wovern fabric and surrounded by a cover *f* of fabric or the like laid around the strips *e e* and fixed to two metal plates provided at the two side surfaces of the ledge *c*.

55 The bolt *n* is pivoted to a foot-plate *g* pressing against the strips *e e*.

60 The way of working of the device is the following. By simultaneously turning the hand-wheels *m*, the pressure in the whole tube and correspondingly the pressure ex-

erted by the whole surface of the rubber-ledge *c* may be regulated to any desired degree.

65 The turning of a single handwheel allows to increase the pressure at the corresponding point of the working surface. The rubber tube *d* may press with a certain flattened area against a part of the rear side of the ledge *c*. If the pressure is increased, the state shown in Figure 3 may be arrived at, and the state shown in Figure 4 by further 65 increasing the pressure. The metal strips *e e* will be bent according to the different positions arrived at by the flattening of the tube *d* at the different points.

70 Now what I claim and desire to secure by Letters Patent is the following:—

75 1. In a machine of the character described the combination of a continuous rubber ledge extending over the machine and flexible to adapt its working face closely to the variations of thickness of the hide, a guide for the ledge, a pneumatic tube disposed along and in contact with the rear face of the ledge.

80 2. In a machine as specified in claim one a series of individually controllable means to apply different pressures to different points of the pneumatic tube and to flatten the same to a different degree against different points of the rear face of the said ledge.

85 3. In a machine of the character described the combination of a rubber ledge sliding between guides, an inflatable rubber tube provided along and in contact with the rear side of said ledge, a pliable metal strip superimposed on the said tube, and means to exert different pressures at different points to the said strip to compress the tube different extents.

90 4. In a machine of the character described the combination of a rubber ledge sliding between guides, an inflatable rubber tube provided along and in contact with the rear side of said ledge, two flexible metal strips superimposed against the said tube, a cover for said tube plied around said metal strips and confining said tube against said rubber-ledge, and means to flex the strips toward the tube through variable and different extents at different points therealong, so as to vary the compression of the tube at different points.

5. In a machine of the character described the combination of a rubber ledge, an inflatable tube provided at and along the rear side of said ledge, pliable metal strips extending along the length of said tube, pressing screws, and foot-plates interposed between the ends of the screws and the pliable strips at different points whereby operation of the screws will flex the strips at different 10 points variable amounts and thereby compress the tube different and variable amounts at the different points.

6. In a machine of the character described, the combination of a continuous 15 flexible ledge, means for supporting the ledge for flexure laterally and thus project to different extents along one face, a pneumatic tube disposed along and in contact with the face of the ledge opposite said one 20 face, and means for variably flattening the tube against the ledge variable and different extents along its length.

7. In a machine of the character described, the combination of a flexible ledge, 25 a support in which the ledge is slidably laterally so as to flex and thereby project to different extents along one face, a pneumatic tube disposed along and in contact with the face of the ledge opposite said one face, a 30 pliable strip extending along the tube, and means for flexing the strip at different points so as to compress the tube against the ledge variable and different amounts along its length.

8. In a machine of the character described, the combination of a flexible ledge, a pair of guides between which the ledge is 35 slidably supported for lateral movement, a pneumatic tube disposed along the ledge so as to exert lateral pressure thereon tending to cause sliding movement of the ledge, a pair of flexible strips arranged side by side along the tube on the side opposite the ledge, a pair of flexible covers, one anchored along 40 an edge to each guide, each cover extending around the adjacent side of the tube and anchored to the adjacent strip, so as to confine the tube between the ledge, strips, and covers, and means for pressing the strips toward the ledge variable and different 45 amounts at different points along the same to exert varying pressures on the ledge.

9. In a machine of the character described, a continuous elongated ledge, flexible laterally in one plane from end to end, 55 an abutment surface extending substantially parallel with the ledge and normal to the plane of flexure of the ledge, a pneumatic tube disposed between the abutment surface and the ledge, and means for varying the pressure on said tube.

10. In a machine of the character described, a continuous elongated ledge, flexible laterally in one plane from end to end, 60 means for preventing flexure in other planes, 65 an abutment surface extending substantially parallel with the ledge, and normal to the plane of flexure of the ledge, a pneumatic tube disposed between the abutment surface and the ledge, and means for creating 70 variable pressures on the said tube for varying the pressure on said ledge.

11. In a machine of the character described, a flexible ledge, means for guiding the ledge for flexure in one plane and preventing flexure in other planes, a pneumatic tube arranged along and in contact with the ledge, a flexible strip arranged along the tube for compressing it against the ledge in the direction of its flexure, means for pressing said strip toward the ledge to compress the tube between them, and flexible strips connected to said guiding means and to said strip at spaced points along the tube. 75

12. In a machine of the character described, a continuous flexible ledge, means for guiding the ledge for flexure in one plane and preventing flexure in other planes, a pneumatic tube placed along the ledge for exerting pressure thereon in its flexing direction, a flat pressure plate extending along 80 the tube upon the side opposite the ledge, and means for flexing the plate in a direction to flatten the tube against the ledge, the tube being substantially unconfined 95 against expansion laterally.

13. In a machine of the character described, a continuous flexible rubber ledge, and means for pressing the ledge in one direction while yieldingly permitting flexure 100 along its length.

In witness whereof, I hereunto subscribe my signature this 5th day of August 1921.

BRUNO PAUL BOHACEK.
